UNITED STATES PATENT OFFICE.

ABEL H. FROST, OF CHICAGO, ILLINOIS.

BUCKLE.

SPECIFICATION forming part of Letters Patent No. 249,829, dated November 22, 1881.

Application filed January 15, 1881. (No model.)

To all whom it may concern:

Be it known that I, ABEL H. FROST, of Chicago, State of Illinois, have invented certain new and useful Improvements in Buckles; 5 and I do hereby declare that the following is a full, clear, and exact description thereof, reference being had to the accompanying drawings, and to the letters of reference marked thereon, which form a part of this specification.

10 My invention relates to the class of buckles which have the tongue hinged to an end bar of the frame and the free end of the tongue supported centrally as to the frame. It is more especially an improvement on the buckle 15 patented to W. T. Reaser in Letters Patent No. 176,053, dated April 11, 1876, wherein the free end of the tongue is shown and described as resting on the central stud, E. In practical use of the buckle mentioned it is found to 20 be difficult to keep the tongue on the stud—that is to say, it slips off to one side. This gives a bad appearance to the buckle and throws the strain sidewise upon the tongue, with danger of its drawing through. I have 25 remedied this fault by making the tongue of such shorter length as to clear the stud entirely, thereby allowing said tongue to rest on an underlying fold of the strap or straps. I have also broadened the central depressed 30 cross-bar upon which the stud is formed, so as to support the leather beneath the free end of the tongue.

In the drawings, Figure 1 is a central longitudinal section of a single strap and buckle 35 through *xx* of Fig. 2; and Fig. 2 is a top view of the buckle and strap.

The same letter indicates the same part in both figures.

H H are the side bars, and B and C are the 40 end bars, of the buckle-frame.

D is the depressed central cross-bar, and E a stud projecting upward from the middle of said cross-bar D.

A is the tongue, hinged to the end bar B. 45 Said tongue A is made of such length as to fairly clear the stud E when dropped down within the frame. The strap or straps F being inserted in the manner contemplated in this

class of buckles, and as indicated in the drawings, the free end of the tongue rests upon an 50 under fold of the leather, instead of upon the stud E, and may, therefore, maintain its natural central position with reference to the frame. In order to prevent the tongue thus shortened from drawing downwardly or inwardly past the cross-bar D, said cross-bar is 55 extended on the side toward the tongue, to support the leather beneath the point on which the free end of the tongue bears, as seen in Fig. 1, and as indicated by dotted lines in Fig. 2. 60

A secondary but material advantage of the construction shown is found in the fact that the tongue, arranged to rest on a fold of the leather, instead of resting upon the stud, serves to hold the lower fold or folds of the strap 65 snugly down to the cross-bar, or about the base of the necessarily tapering stud, whereby the full strength of the stud is made available and all parts lie more closely together. By curving the tongue to bear broadly upon the 70 strap, as shown in Fig. 1, said strap being supported by the cross-bar D in the manner described, strain upon the buckle does not materially tend to draw the tongue into the surface upon which it rests. 75

While the cross-bar D is shown in Fig. 2 as having a curved edge, or as being made broad, for the purpose stated only in its central portion, it may obviously be of equal breadth throughout its length. 80

I claim as my invention—

In the buckle described, having the central depressed cross-bar, D, provided with the stud E, the tongue A, hinged to the end bar B, and made of such length as to clear the stud, and the cross-bar D extended to give support to the leather beneath the end of the tongue, substantially as described, and for the purposes set forth. 85

In testimony that I claim the foregoing as 90 my invention I affix my signature in presence of two witnesses.

ABEL H. FROST.
